TYPEWRITING MACHINE

William F. Helmond, West Hartford, Conn., assignor to Underwood Elliott Fisher Company, New York, N. Y., a corporation of Delaware

Application March 9, 1936, Serial No. 67,884

14 Claims. (Cl. 197—138)

This invention relates to the work-piece feeding and guiding devices of typewriting machines.

The work-piece is held in yielding contact with the platen by rolls mounted in frames which permit the withdrawal of the rolls. Commonly auxiliary feed-rolls press the work-piece smoothly against the platen above the printing point.

The auxiliary feed-rolls are usually carried on a bail, which may swing the rolls above and to the rear of the platen to free the work-piece. Or the rolls may be drawn forwardly of the platen, leaving a clear space to permit an introduced work-piece to advance upwardly without manipulation by the operator.

15 The usual mechanism is such that the returning feed-rolls are brought directly downward, and the middle bowed-out portion of a stiff work-piece, which does not bend naturally around the platen, may be struck or fouled by the returning rolls, and creased, or caused to bulge, at the printing point. It has been proposed to bring the rolls to rest forwardly of the platen, and loosely confine the work-piece. Such construction necessitates additional manipulation by the operator 25 to carry the rolls rearwardly and bring the work-piece into printing position.

It is a feature of this invention to provide an auxiliary feed-roll structure in which the feed-rolls, when the bail is given a single short pull or 30 impulse by the operator, will swing downwardly from the released position with a radius of rotation sufficient to bring the feed-rolls to a position in front of the work-piece, and then in a continuing motion without additional manipulation 35 move rearwardly against the platen, drawing the work-piece into proper writing position.

The radius of swing of the feed-roll bail is sufficient to clear the work-piece, regardless of the position assumed by the work-piece when freed 40 by elevating the feed-roll structure.

The feed-rolls are drawn against the platen with sufficient force to hold stiff work-pieces or work-packs.

The feed-rolls may be yieldably held forward 45 of the platen, and may be swung upwardly into released position directly from the forward position, or brought from the released position directly to the forwardly-held position.

The side arms of the feed-roll bail are swing- 50 ably and slidably mounted upon the platen-frame. An overthrow spring swings the side arms forwardly after a portion of the upward swing has been traversed, thus extending the radius of the arc of swing. With the feed-rolls in the released 55 position, a short forward pull by the operator will

cause them to swing downwardly against the resistance of the overthrow spring, the extended radius being sufficient to bring the feed-rolls outside of the work-piece. One or both of the side arms may be provided with a cam which, near 5 the completion of the down stroke of the bail, co-operates with a fixed pin or abutment to direct the bail-structure rearwardly. The rearward motion of the bail, and the accumulated momentum thereof, are sufficient to cause the overthrow 10 spring to pass its dead-center position, whereupon the subsequent reaction of the spring completes the rearward motion of the bail, and brings the feed-rolls into operative position.

Means are also provided to enable the auxiliary 15 feed-rolls to be raised clear of the platen jointly with casting off the main feed-rolls, to permit adjustment or manipulation of the work-piece.

This invention also discloses a platen-frame 20 having a rear paper-table composed of hinged sections, one of which sections may be swung upwardly to afford access to the usual tabulator-rack. The usual flat tie-bar which spans the platen side plates is replaced by a tie-rod, which 25 additionally serves as the hinge-pin for the paper-table.

It is an object of this construction to simplify the platen-frame by eliminating the short pintles commonly used to pivot a hinged paper-table, and 30 making it possible to form the knuckle of the paper-table hinge with only three interfitting sections. The knuckle thus includes a short tongue at each end of the fixed section of the paper-table, and an unbroken, central tongue, 35 wider than the work-piece for which the platen-frame is designed, by which the movable section is pivoted on the tie-rod.

Additional advantage may be taken of this construction by forming the usual centering scale 40 on the central tongue, which may be so shaped as to present a pleasing convex surface.

The hinged section of the paper-table may be yieldingly held in normal position against suitable abutments projecting from the platen side 45 plates, the said abutments preferably being padded to prevent the generation of vibratory noises during operation.

Other features and advantages will hereinafter appear. 50

In the accompanying drawings.

Figure 1 is a perspective, illustrating the invention as applied to the platen-frame of an Underwood standard typewriter.

Figure 2 diagrammatically shows the co-opera- 55

tion between the main feed-roll-release mechanism and the upper feed-roll bail.

Figure 3 is a perspective, illustrating the assembly of the bail-operating mechanism at the right-hand side arm.

Figure 4 illustrates the position of the feed-roll bail when thrown back completely out of use.

Figure 5 shows the direction of the line of action of the spring after the bail side arm has been directed rearwardly on the return from released position.

Figure 6 is a sectional view of the platen-frame of Figure 1, additionally showing the carriage-frame and supporting members.

Figure 7 illustrates the path taken by the feed-rolls on returning the bail from released to operative position.

Figure 8 diagrammatically illustrates the extension of the radius of rotation of the feed-roll bail when being swung upwardly into released position.

Figure 9 illustrates the bail drawn forwardly into position for erasures or work-sheet manipulation.

Referring to Figure 6, a carriage-frame 15 of an Underwood typewriter runs upon front and rear rails 16, 17, supported by standards of the machine-frame.

The carriage has a platen-frame 24 case-shiftable by the usual shift mechanism, which, because of familiar design, has been omitted from the drawings in the interests of clarity. Figure 6 shows the frame in the lower-case position, with a stop 19, secured to platen-frame side plates 20 resting on a shoulder 21 of a clamp 22 which secures a case-shift fulcrum-rod 23.

A rear paper-table 25 is formed of hinged sections 26, 27, the hinge-pin being a tie-bar 28, Figure 6, of substantial strength, spanning and re-enforcing the said side plates 20, and secured thereto by screws 29, the right-hand screw being shown in Figure 1. A platen 30 is journaled in the side plates on an axle 31, with the usual knob (not shown) provided at the end thereof to afford means for manual rotation of the platen.

The front section 27 (Figure 6) of the paper-table has an apron 33 curving around the bottom of the platen to direct a work-piece 34 between the platen and releasable main feed-rolls 35, 36 and up into printing position above the wing-scales 38, at which types 31 print. Arms 39, 40 support spindle-rods 41, 42 for the main feed-rolls 35, 36, said arms extending respectively forwardly and rearwardly from a common fulcrum-rod 43, supported at its ends by the platen-frame side plates as at 44, Figure 1. Springs 45 acting upon the arms 39, 40, serve to press the main feed-rolls 35, 36 against the platen.

For rocking the main feed-roll-carrying arms 39, 40 jointly about the common fulcrum-rod 43, to withdraw and thereby release the main feed-rolls from the platen, the mechanism includes a cam-shaft 46, journaled in hangers 47 (Figure 1) depending from the fulcrum-rod 43. Cam-shaft 46 has camming flats 48, Figure 6, which may coact with arms 50, 51, connected respectively to the main feed-roll-spindle-supporting arms 39, 40. Any suitable number of pairs of the main feed-rolls 35, 36 may be provided, and all may be operable from the common cam-shaft 46. A manually-operable feed-roll-release lever 52, comprising an arm 53 (Figure 6) provided with a finger-piece or handle 54 and a second arm 55, is pivoted upon a fulcrum-stud 56 extending from one of the side plates 20, said arms having a com-

mon hub. The arm 55 may be connected by a link 57 to a crank 58 of the feed-roll-releasing cam-shaft 46.

Upper feed-rolls 60, Figure 1, which yieldingly hold the work-piece against the platen 30, may be slidably mounted to rotate on a shaft or rod 61. The rod is removably secured, as by screws 62, to side arms 63, 64, the forward ends 65 of which, turned in at right angles as shown, form means of rigidly supporting the rod 61. The rod 61 and side arms form a bail 66 of substantial strength. The three parts of the bail may be completely finished as to plating, polishing, etc., before assembly, and the component parts, including the rolls 60, are easily replaceable.

At the rear ends thereof, the side arms 63, 64 are formed with a head-portion 67, in which a longitudinal slot 68 is cut. Intermediate the slotted portion, the heads 67 are provided with a tongue 70, which near its end is provided with a headed pin 71.

A rock-shaft 72 is journaled in the side plates 20 above and to the rear of the platen 30, the said shaft passing through the slots 68 of the side-arm heads 67. At the right-hand end, the shaft 72 is formed with milled flats 74 (Figure 3), and a crank 75, formed with a hole shaped to co-operate with the flattened end of shaft 72, is thereby held on the said shaft against independent rotation. The crank 75 is mounted outside of 30 the right-hand side plate, and may be removably secured to the shaft 72 by a screw 76.

The shaft 72 is of sufficient length to provide for slight manufacturing discrepancies in the overall width of the platen-frame, the end 72a of 35 the said shaft projecting through the left side plate 20, as shown in Figure 1.

The bail side arms 63, 64 are swingably and slidably held between washers 77, Figure 1, and forked cranks 78, the said cranks being mounted 40 on the shaft 72 and securely held adjacent the side arms as by the set-screws 80. The pins 71 of the tongues 70 extend to work within the forked end of the corresponding crank 78. The shaft 72 is held against excessive sideplay by 45 the co-operation of the forked cranks 78 and the crank 75.

Forward of the tongue 70, the left side arm 63 is formed with an extension 81, Figure 5, having a rearwardly and downwardly sloping cam-surface 50 82 to coact with a pin 83 projecting inwardly from the left side plate 20, as later described.

A tensile spring 84 is anchored, below the center line of the rock-shaft 72, on a suitable pin or screw 85 projecting from a lug 86 extending 55 downwardly from the right-hand side plate 20. The pin 85 may co-operate with a screw 87 in securing the case-shift stop 19. The forward end of the spring 84 is hooked around a pin or stud 88 projecting from the crank 75, the said pin being formed with a groove or slot to receive the spring. The spring 84 and the crank 75 preferably underlie the flanged surface 89 of the side plate 20, and may be concealed from view by 65 the customary sheet-metal mask (not shown) with which the side plates 20 are customarily provided.

The crank 75 and the forked cranks 78 are so placed on the shaft 72 that when the feed-rolls 60 70 are in operative position, as seen in Figure 6, the stud 88 of the crank 75 is below the center line of the rock-shaft 72, and the spring 84 thereby urges the shaft 72 in a rotation clockwise of Figure 6, causing the forked cranks 78 to draw 75

the side arms 63—64 rearwardly to the extent of the slots 68.

Lifting the bail 66, preferably by an upward finger-pressure on the under side of the rod 61, causes a rotation of the rock-shaft, counterclockwise of Figure 6, through the co-operation of the pin-and-slot engagement of the forked crank 78 and the tongue 70. The corresponding movement of the crank 75 places the spring 84 under increasing tension. After a partial upward swing of the bail, as shown diagrammatically in Figure 8, the crank 75 will have brought the line of action of the spring 84 above the center line of the rock-shaft. The immediately following reaction of the spring 84 causes the rock-shaft 72 to rotate sharply, and again through the co-operation of the forked crank 78 and pin 71 at each side arm the said arms are thrown or "kicked" forward to the full extent of the slotted heads 67, and the arc of upward rotation of the bail is consequently increased in radius, as represented in the dotted line in Figure 8. The side arms come to rest in the released position, Figure 8, against a gaging pin 90 projecting from the right side plate 20.

By giving the feed-roll rod 61 a quick, forward, flip or pull, the feed-roll bail 66 may be returned from the released position to operative position in a continuous motion, the novel path taken by the feed-rolls being indicated by dotted lines in Figure 7. The force of the pull to start the bail-movement need only be great enough to overcome the resistance of the spring 84, which, when the feed-roll bail is in the released position, 35 is not large, and to give to the bail-structure a slight momentum. The weight of the bail-structure, as it passes the vertical position, adds to the force of the descent, and aids in overcoming the increasing tension of the spring 84.

As shown in Figure 7, the arc of travel is at maximum radius until the cam 82 strikes the pin 83. The slope of the cam directs the side arms rearwardly, causing the rock-shaft 72 to continue to rotate, until the crank 75 brings the spring 84 below the center line of the rock-shaft, as shown in Figure 5, whereupon the action of the spring, operating through the forked cranks 78, pulls the side arms 63, 64 rearwardly to the "home" position. The extended radius of side arms 63, 64 during the larger portion of the downward travel of the bail is sufficient to bring the feed-roll rod 61 outside of the work-piece 34, as shown in Figure 2, and the subsequent rearward movement of the bail draws the work-piece smoothly against the platen. In addition, the upper feed-rolls 60 tend to ride up on the platen, thus acting to "iron out" the work-piece.

It will be obvious from Figures 7 and 8 that the arrangement is such that the feed-roll, in moving to its cast-off position above the platen and in its restoring movement, takes an orbital path in which the return movement is substantially forward of the path of casting off movement, in order that the returning feed-roll does not foul the loose end of the work sheet.

The action of the spring 84, in constantly urging the feed-roll bail into rotation against the platen, provides for continuous compensation for wear of the upper feed-rolls 60.

The feed-roll bail may be drawn forwardly from the operative position to a position shown in Figure 9, in which the feed-rolls 60 are brought clear of the work-piece 34 to facilitate the insertion of a new work-piece, or when making erasures. The forward ends 65 of the side arms 63, 64 may

be formed with upwardly and rearwardly curving extensions 91 which form convenient handles with which to draw the feed-roll bail forwardly. The bail may be latched in the forward position by engaging the pin 83 in a detent-notch 92 formed in the cam-extension 82. As indicated in Figure 9, the forward movement of the bail 66 will, through the co-operating pins 71 and forked cranks 78, rotate the shaft 72 to a point at which the face of the spring 84 is applied above the rock-shaft 72, and thus the side arms will be yieldably held in the desired position. To return the feed-rolls 60 to operative position, the operator need only push on the feed-roll rod 61, and the crank 75, being again rotated to a point below the shaft 72, will cause the spring 84 to pull the rolls against the platen.

To bring the feed-roll bail from the released position of Figure 8 to the position of Figure 9, the operator need only retain control of the bail, 20 bringing it down more slowly, and latching the notch 92 into engagement with the pin 83. The detent-notch 92 is expressly made sufficiently shallow to permit the operator to swing the bail from the position of Figure 9 to the position of 25 Figure 8 by a light upward pressure applied beneath the feed-roll rod 61. The bail-structure may also be swung upwardly to a position of complete disuse, as in Figure 4, in which it may be held by pressing the bail-structure downwardly 30 so that a shoulder 93 of the side arm 64 is held by the pin 90.

It is a desirable feature of this invention that when the bail is thrown from the released position toward operative position against the platen, 35 the increasing resistance of the spring 84 "brakes" the force of the descent.

The upper feed-roll bail 66 may also be lifted to raise the top feed-rolls 60 off the platen conjointly with casting off the main feed-rolls 35, 40 36 through the co-operation of a stud 94, Figure 2, provided on the link 57 of the main feed-roll release, and an extension 95 formed on the right-hand side arm 64. The stud 94 is operative, as shown in Figure 2, to raise the bail 66 45 at operation of the main feed-roll-release lever 52, the full depression of which rotates the cam-shaft 46 to its fully operative feed-roll return checking position, causing the feed-rolls 35, 36 to be swung clear of the platen and held in released position. The bail 66 is consequently held in released position. The top and bottom feed-rolls may be returned to operative position by an upward movement of the lever 52, or by pressing down on the upper feed-roll bail 66. For 55 making adjustments of the work-piece position, the lower feed-rolls 35, 36 and the upper feed-rolls 60 may be partially released by a partial depression of the lever 52, whereby, with the release of the said lever, the springs 45 return the 60 main feed-rolls to operative position, and the feed-roll-bail spring 84 brings the upper feed-rolls into contact with the platen.

When the lower feed-rolls 35, 36 are released when the upper feed-roll bail 66 has been drawn forwardly, as when a new work-piece is being inserted, the operator, by pushing the feed-roll bail back to operative position, also casts the lower feed-rolls on through the co-operation of a ramp 96, Figures 1 and 6, at the rear of the extension 70 95, which, by engaging the stud 94, cams the link 55 downwardly, and thus actuates the main feed-roll-release mechanism.

In the foregoing description, and the drawings applicable thereto, the camming extension 81 75

has been shown only on the left-hand side arm 63 of the bail 66. However, for wide-carriage machines, it may be desirable to include such a camming device on the right-hand side arm 64, to prevent any possibility of distortion as the bail-structure is being swung into operative position.

The two sections 26 and 27 of the rear paper-table 25 may be considered as being the leaves of a hinge, the tie-bar 28, which serves primarily as a re-enforcing member for the platen-frame 24, forming the hinge-pin. The knuckle of the hinge may include narrow tongues 100 at the ends of the section 27, the said tongues curving around the tie-bar 28, as shown in Figure 1. The rear section 26 is pivotally secured to the tie-bar by a tongue 102 also curved around the said bar. The width of the tongue 102 is greater than the width of the work-piece for which the platen-carriage is designed, and on the unbroken surface of the tongue 102 a centering and line-gaging scale 103 may be imprinted. A transverse groove 104 may be pressed into the rear section 26, the said groove being substantially parallel to the tie-bar 28, and acting to form, with the downward sweep of the tongue 102 where it curves around the said tie-bar, an attractive convex surface which imparts a maximum of legibility to the graduations of the scale 103. It will be seen from Figure 1 that the operator's view of the scale is not obscured by the feed-roll bail rock-shaft 72.

At each end of the section 26, a flange 106 is turned downwardly as shown in Figures 1 and 6, to strengthen the said section, and to serve as a support for a side-gage-supporting rod 107. Springs 108, coiled around the tie-bar 28 at each end of the platen-frame, have one end anchored in a hole 110 in each side plate 20, and the other end hooked into the flange 106, as shown in Figure 1. The springs 108 act to rotate the section 26 downwardly about the tie-bar 28, and hold the said sections yieldingly against upwardly offset tongues 111 of a pair of lugs 112 extending inwardly from each end plate 20. The tongues 111 are preferably padded, as by the felt ring 113, to eliminate the production of vibratory noises during operation.

A side gage 114, of familiar design, is mounted on the rod 107, so as to be slidable across the paper-table section 26. As clearly indicated in Figures 1 and 6, the forward edge of the side gage 114 curves into the groove 104, and thereby extends into close proximity with the scale 103, but does not rub across the graduations thereof. The position of the side gage is thus clearly designated by the scale, and the latter remains free from the possibility of defacement by the side gage, regardless of the number of times the side gage is shifted by the operator to center or gage the position of the work-piece with respect to the platen.

As shown in Figure 6, the typewriter may include a tabulator-rack 115, of familiar design, supported on the carriage-frame 15 as by a strap 116. Tabulator-stops 117 may be held on the said rack by co-operating tines 118. A tabulator-key actuated counter-stop 119 co-operates with the said stop 117 in the usual manner to arrest the travel of the carriage at established tabulating positions. Such devices are well known in the art. To assist in locating the tabulator-stops, to establish the tabulating positions, a scale 120, mounted above the tabulator-rack 115, as by standards 121, is provided.

As indicated by dotted lines in Figure 6, the rear portion of the paper-table may be swung forwardly to permit access to the tabulator-stops 117, and the scale 120.

Variations may be resorted to within the scope of the invention, and portions of the improvements may be used without others.

Having thus described my invention, I claim:

1. In a typewriting machine, the combination with a platen and a platen-frame, of a feed-roll-carrying bail, a rock-shaft in said frame, the said bail having side arms pivotally mounted on and radially movable relatively to said rock-shaft, the said side arms being operatively associated with the rock-shaft by a crank and pin connection, an overthrow spring-device acting upon said rock-shaft to cause radial movement and thereby an automatic change in the radius of rotation of the bail side arms when the bail is swung upwardly of the platen, and means including a cam-device on one of the side arms of the said bail to direct the bail rearwardly on the return of the feed-rolls to operative position, the rearward motion of the bail enforcing a rotation of the said rock-shaft sufficient to cause the overthrow spring-device to complete the rearward movement of the said bail.

2. In a typewriting machine, the combination with a platen and a platen-frame, of a rotatable shaft in said frame, a feed-roll-carrying structure connected to said shaft for rotating therewith and moving radially thereof, and an overthrow spring connected to said shaft to rotate the latter in opposite directions and concomitantly move said structure radially in opposite directions.

3. In a typewriting machine, the combination with a platen and a platen-frame, of a feed-roll bail adapted to swing about an axis and to move radially of said axis, and a device coacting with said bail to automatically move the bail radially in response to a swing of the bail either to or from the platen about said axis.

4. In a typewriting machine, the combination with a platen and a platen-frame, of a top-feed-roll bail, a rotatable mounting for said bail in said frame, said mounting and bail being connected so that the bail may rotate with and move radially of said mounting, and a device coacting automatically with said mounting to move said bail radially in response to a swing of the bail either to or from the platen.

5. In a front-strike typewriting machine, the combination with a platen and a platen-frame, of a top-feed-roll bail comprising a roll-bearing rod extending longitudinally of said platen and side arms having outer ends spanned by said rod, said side arms extending rearwardly, and adapted to swing and to move radially of the axis of swing so that the roll-bearing rod may be drawn forwardly of the platen or swung upwardly into a released position above the platen, and a device acting upon said side arms, in response to upward swing thereof, to move said arms radially to cause an automatic change in the radius of rotation of the bail.

6. In a front-strike typewriting machine, the combination with a platen and a platen-frame, of a feed-roll bail comprising a roll-bearing rod extending longitudinally of said platen and side arms having outer ends spanned by said rod, said side arms extending rearwardly to an axis of swing behind the platen, and adapted to swing and to move radially of the axis of swing, the said roll-carrying rod thus being capable of be-

ing swung upwardly from and downwardly toward the platen, and a device coacting with said side arms, in response to their upward and return swing, to move said arms radially, whereby 5 when the said rod is allowed to swing downwardly, the said feed-roll rod descends to a position forwardly of the platen and thence is caused to move rearwardly to operative position, with the feed-rolls against the platen, without 10 manipulation by the operator.

7. In a typewriting machine, the combination with a platen and a platen-frame, of a pivotally mounted bail having a front rod carrying a feed-roller co-operative with the top of said platen, 15 and a device acting automatically, to give the said bail an increased radius of rotation, in response to swinging the bail upwardly off the platen, said device being arranged to control the bail so that as the bail is returned toward operative position, the increased radius is retained over a portion of the return travel and is then normalized to bring the said bail into operative 20 position.

8. In a typewriting machine, the combination with a platen and a platen-frame, of a top-feed-25 roll carrying bail, arranged to swing about and move radially of an axis behind the platen, a device acting automatically, to move said bail radially and thereby give said bail an increased 30 radius of rotation, in response to swinging the bail upwardly off the platen, and a camming device operative upon said bail and coacting with said first mentioned device to move the bail radially toward the platen after a certain portion 35 of the return movement of the bail at the increased radius has been traversed.

9. In a front-strike typewriting machine, the combination with a platen and a platen-frame, of a feed-roll, a supporting structure therefor in 40 said frame and having a fulcrum behind the platen, whereby the feed-roll is swingable upwardly in a certain path from a position on the platen above the printing line, said structure being adapted for returning the feed-roll in a 45 different path forwardly of said upward path and eventually back to said position, and a device adapted to co-operate with and govern said structure automatically to determine automatically, and consonantly with the upward swing and return of said feed-roll, said different upward and return paths.

10. In a front-strike typewriting machine, the combination with a revoluble platen and a platen-frame, of a bail pivotally mounted so as 55 to be swingable at a variable radius about an axis behind the platen, said bail mounting a feed-roller co-operative with the said platen at a position above the printing line, means acting automatically to give the said bail an increased 60 radius of rotation in response to swinging the bail upwardly off the platen, and a cam on the bail and arranged to engage with an abutment on said platen-frame when the feed-roll bail is swung downwardly, whereby the radius of rotation will be so shortened as to direct the feed-65 roll rearwardly toward said position against the platen, said means being adapted to move said bail radially to bring the feed-roll finally to said position in response to the engagement of said 70 cam with said abutment.

11. In a front-strike typewriting machine, the combination with a platen and a platen-frame, of a bail pivotally mounted so as to be swingable at a variable radius about an axis behind the platen, said bail mounting a feed-roller co-operative 5 with the said platen at a position above the printing line, a device and an overthrow-spring governing said device for automatically giving the said bail an increased radius of rotation in response to swinging the bail upwardly off the 10 platen, and a camming device associated with the said bail to direct the bail rearwardly against the platen after a portion of return movement of the bail at the increased radius has been traversed, the said rearward direction of the bail by said 15 cam-device causing said overthrow spring to govern said device to complete rearward radial movement of the bail and thus to draw the feed-roll against the platen.

12. In a front-strike typewriting machine having 20 a platen-frame, a platen journaled therein, a main feed-roll co-operative with the under side of the platen, a controller shiftable oppositely to cast off and restore said main feed-roll, a swingably and radially movable bail mounting 25 an upper feed-roll, said bail being capable of being moved radially to a position to draw the upper feed-roll forward of the platen and being yieldably held in said position, an operative connection between said bail and controller where- 30 by the said bail may be swung to lift the upper feed-roll clear of the platen conjointly with the casting off of the main feed-roll by said controller, said connection being adapted so that if the main feed-roll and controller are moved to 35 casting off position while the upper feed-roll is in the aforesaid forwardly drawn position, the upper and lower feed-rolls may be conjointly returned to operative positions by means of said connection by pushing rearwardly against the 40 upper feed-roll.

13. In a front strike typewriting machine, the combination with a revoluble platen, of a top feed-roll to hold a work-sheet above the printing point against the platen, a bail for said roll, 45 supporting means for said bail adapted to permit said roll to be moved forwardly from the platen and back, or to be raised from the platen and lowered from said raised position to a position in front of said platen, and a spring-device 50 acting automatically to cause the path of said roll when lowered to be forward of the path in which it is raised.

14. In a front strike typewriter, the combination with a revoluble platen and a top feed-roll 55 or the like to hold a work sheet to the platen above the printing line, of means mounting said feed-roll for movement to a cast-off position above the platen and for restoring movement, and a device coacting with said mounting means 60 to direct automatically the casting off and return movements of said feed-roll in an orbital path, so that automatically the return path of movement is caused to be substantially forward of the casting-off path of movement of said feed-65 roll, whereby at the return of the feed-roll the latter does not foul the loose end of said work sheet.
